ENGINE STARTER

James A. Charter, Chicago, Ill., assignor to
Charter Drive, Inc., Chicago, Ill., a corpora-
tion of Illinois

Application July 27, 1931, Serial No. 553,338

12 Claims. (Cl. 74—9)

This invention relates to engine starters and has for its object to provide a new and improved device of this description. The invention is particularly adapted to be used in connection with engine starters for internal combustion engines used on automobiles and the like. One of the objects of the present invention is to produce an engine starter which can be produced at a low cost and which is efficient in construction and 10 operation. The invention has as a further object to produce an engine starter wherein the machining operations are reduced and simplified. The invention has other objects which are more particularly pointed out in the accompanying description.

Referring now to the drawing, Fig. 1 is a view of one form of engine starter embodying the invention;

Fig. 2 is an end view of the device illustrated in Fig. 1;

Fig. 3 is a plan view of the driving pinion;

Fig. 4 is an end view of the collar forming a part of said pinion before the toothed section is connected therewith;

Fig. 5 is a sectional view taken on line 5—5 of Fig. 3;

Fig. 6 is the stop lug forming a part of the driving pinion.

Like numerals refer to like parts throughout the several figures.

Referring to the drawing wherein I have illustrated one construction embodying the invention, I provide a sleeve 1 into which the drive shaft of the starting motor is received, the sleeve being connected to this shaft so as to rotate therewith. Mounted upon the sleeve 1 is a driving member adapted to be connected with some part of the engine to be started, such for example as the fly wheel. This driving member as a whole is designated as 2. It comprises a gear 3 having teeth 4 thereon. The top portion of the teeth 4 at one end of the gear part way therealong are cut away or turned down or otherwise formed so as to be below the tops of the remaining portion of the teeth, the cut away portion being indicated at 5. This provides a gear having the long teeth 4 and the short teeth 5. The end of the gear containing these short teeth projects into the collar 6, which has an eccentric opening 7 and which is provided with teeth 8 which fit between the teeth 5 on the gear. The gear is forced into the collar until the shoulder 9 on the gear engages the collar.

I prefer to have the longitudinal dimension of the short teeth somewhat greater than the thick-

ness of the collar so that they will project a short distance beyond the collar when in position. The collar is preferably slightly beveled at 5a on that face from which the end of the gear projects, and the extended metal of the teeth is then forced into the bevel of the collar and smoothed off to an even surface. It will be seen that the gear and the collar are then completely united.

The eccentric collar 6 is provided, on the side which has the greater thickness of metal, with a slotted opening 10 which extends along the collar, as shown in Fig. 3, and there is also provided a slot 11 connecting therewith and connecting with the face of the collar. The two slots form a T-shaped slot in the collar. This slot is for receiving the hooked end 12 of the coil spring 13, the hooked portion 12 fitting into the slot as shown. These slots are formed in any desired manner, but are preferably formed by means of a circular saw shaped milling cutter, as this greatly facilitates the making of the slots and greatly cheapens the construction.

Connected with the collar 6, on the side opposite the slots 10 and 11, is a stop lug 14. This stop lug may of course be integral with the collar, but I prefer to have it separate from the collar, as shown in Fig. 6, and to electrically weld it thereto by a fusion welding operation, thereby greatly cheapening the construction. The stop lug 14 is provided with a projection 15 which extends over the first coil on the back side of the spring 13. The purpose of this projection is to prevent any possible tilting of the spring in relation to the face of the coil 6, thus forming a comparatively rigid positioning of the spring in relation to the face of the eccentric shaped collar of the starting element. The stop lug 14 has a flat face 16 on one side of the projection 15 and a serrated face on the other side of the projection 15, the serrations extending across the face. These serrations are brought into contact with the collar 6 and are fused in the welding process and insure a permanent complete uniting of the stop lug with the collar.

The collar 6 is preferably made from solid round bars or rods of the proper metal, which are regular stock and therefore low in cost. These bars are then severed into pieces of the proper length and bore eccentrically, the bore being serrated or provided with teeth. This provides a collar with a smooth outer periphery which needs no machine work upon it. By providing the collar with the eccentric opening, the metal on one side of the opening, where the slots are placed, is thicker and of greater weight than

on the other side. The slotting of the collar reduces this weight and the amount of metal at this point, but the thickness of the metal is sufficient to maintain the proper strength. The eccentric hole in the collar is so placed that when the metal is removed to form the slots 10 and 11, the collar will be just balanced, with the stop lug 14 added on the opposite sides as shown. This eccentric placing of the hole in the collar, therefore, provides a compensating feature of providing a balanced condition when the driving element is completed, and without adding any additional device or material which has no other function than to assist in securing the balance. This eccentric placing of the opening in the collar also provides for a proper depth of the slot without an unduly large or heavy collar and without extra weight, and still permits the maintaining of a balanced condition. It will further be noted that the stop lug 14 and the slot 11 project in the same direction.

In addition to the cheapening of the construction, this arrangement makes it possible to use materials of different strengths. The stop lug 14, for example, being small, can be made of stronger metal than the collar 6, that is of metal containing a greater amount of carbon. If the stop lug 14 was integral with the collar, it would necessarily be of metal of the same strength and would have to be larger and heavier. When the device is heat treated, the stop lug 14, having a greater amount of carbon, will become harder and will therefore wear longer than if made of the same metal as the collar. The sleeve is connected with the shaft 18 of the starting motor 17 by the screw 18a. The part engaged by the driving member is indicated at 19. The sleeve 1 is provided with a projection or stop 20 which, under predetermined conditions, is engaged by the stop lug 14.

I claim:

1. An engine starter comprising a rotatable part, a driving member rotatably and slidably mounted thereon, and comprising a gear having 45 teeth which are adapted to engage the driven part, said teeth for a portion of their length being shorter radially than the remaining portion of the teeth, a collar separate from the gear of harder material than the gear and encircling 50 said shorter teeth and fastened thereto, a laterally projecting stop lug connected with said collar, and a stop projecting laterally from said rotatable part and engaging said stop lug when the parts are in a predetermined position to 55 transmit power from the shaft through said lug to said gear, said stop lug being of harder material than said gear so that it will stand the strain placed thereon.

2. An engine starter comprising a rotatable 60 part, a driving member rotatably and slidably mounted thereon, and comprising a gear having teeth which are adapted to engage the driven part, said teeth for a portion of their length being shorter radially than the remaining portion 65 of the teeth, a collar separate from the gear, said collar provided with teeth intermediate the short teeth on the gear, said collar being rigidly connected with said gear and a stop lug projecting laterally from said gear, said stop lug 70 provided with a projection extending therefrom adapted to prevent tilting of the coil spring which surrounds the rotatable part.

3. An engine starter comprising a rotatable 75 part, a driving member rotatably and slidably mounted thereon, and comprising a gear having

teeth, a collar having an eccentric opening therein, the end of the gear projecting into said opening and fastened to said collar, said collar being provided with a recess, where the material thereof between the periphery of the collar and the eccentric opening is the thickest, said recess adapted to receive the end of the spring associated with the rotatable part. 5

4. An engine starter comprising a rotatable part, a driving member rotatably and slidably mounted thereon, and comprising a gear having teeth, a collar having an eccentric opening therein, the end of the gear projecting into said opening and fastened to said collar, said collar having a portion of the material thereof removed, 15 at the point where the metal thereof between the periphery of the collar and the eccentric opening is the thickest, to form a T-shaped slot.

5. An engine starter comprising a rotatable part, a driving member rotatably and slidably mounted thereon, and comprising a gear having teeth, a collar having an eccentric opening therein, the end of the gear projecting into said opening and fastened to said collar, said collar having a portion of the material thereof removed, 25 at the point where the metal thereof between the periphery of the collar and the eccentric opening is the thickest, to form a T-shaped slot, a stop lug separate from said collar and attached thereto at a point opposite said slot, said stop 30 lug having a portion which projects laterally from said collar.

6. An engine starter comprising a rotatable part, a driving member rotatably and slidably mounted thereon, and comprising a gear having 35 teeth, a collar having an eccentric opening therein, the end of the gear projecting into said opening and fastened to said collar, said collar having a portion of the material thereof removed, at the point where the metal thereof between the 40 periphery of the collar and the eccentric opening is the thickest, to form a T-shaped slot, a stop lug having a projection thereon, the stop lug being provided with a flat face on one side of said projection and a serrated face on the other 45 side of the projection, the serrated face being connected with said collar.

7. An engine starter comprising a rotatable part, a driving member rotatably and slidably mounted thereon, and comprising a gear having 50 teeth which are adapted to engage the driven part, a collar connected with said gear, a stop lug having a projection thereon, said stop lug having a flat face on one side of said projection and a serrated face on the other side of said projection, the serrated face being connected with 55 said collar.

8. An engine starter comprising a rotatable part, a driving member rotatably and slidably mounted thereon, and comprising a gear having 60 teeth, a collar having an eccentric opening therein, the end of the gear projecting into said opening and fastened to said collar, a portion of the metal of said collar, at the thickest portion of its periphery, being removed to form a T-shaped 65 slot.

9. An engine starter comprising a rotatable part, a driving member rotatably and slidably mounted thereon, and comprising a gear having teeth, a collar having an eccentric opening therein, the end of the gear projecting into said opening and fastened to said collar, a portion of the metal of said collar, at the thickest portion of its periphery, being removed to form a T-shaped 70 slot, and a stop lug separate from said collar 75

and attached to the periphery thereof at a point opposite said slot.

10. An engine starter comprising a rotatable part, a driving member rotatably and slidably mounted thereon, and comprising a gear having teeth, a collar having an eccentric opening therein, the end of the gear projecting into said opening and fastened to said collar, a portion of the metal of said collar, at the thickest portion of its periphery, being removed to form a slot, and spring, the end of which is received in said slot.
- 5
10. An engine starter comprising a rotatable part, a driving member rotatably and slidably mounted thereon, and comprising a gear having teeth, a collar having an eccentric opening therein, the end of the gear projecting into said opening and fastened to said collar, a portion of the metal of said collar, at the thickest portion of its periphery, being removed to form a slot, and a stop lug separate from said collar and attached to the periphery thereof at a point opposite said slot, the portion of metal removed from said collar to form the slot being of an amount to bring the parts into a substantially balanced condition when the stop lug is attached to said collar.
- 15

11. An engine starter comprising a rotatable part, a driving member rotatably and slidably

mounted thereon, and comprising a gear having teeth, a collar having an eccentric opening therein, the end of the gear projecting into said opening and fastened to said collar, a portion of the metal of said collar, at the thickest portion of its periphery, being removed to form a slot, and spring, the end of which is received in said slot.

5

12. An engine starter comprising a rotatable part, a gear having an opening through which the rotatable part extends, a collar on said gear, said collar being provided with a slot opening out through the side of the collar extending from the periphery toward the rotatable part, a spring surrounding said rotatable part and having one end thereof received in said slot, said spring projecting laterally from said slot.
